[57] CLAIM

The ornamental design for a sewer line proofer tool, substantially as shown and described.

DESCRIPTION

FIG. 1 is a side elevational view of a sewer line proofer tool showing my new design;

FIG. 2 is a front elevational view thereof; and
FIG. 3 is a rear elevational view thereof.

The broken line representation of a nozzle in FIG. 1 is for purposes of illustration only.

Fig. 2
